OF GERMANY

PHOTO-ELECTRIC MODULATING SYSTEM

Application filed November 12, 1930, Serial No. 495,060, and in Germany November 15, 1929.

The frequency band in electric television, as is well known, is so wide that carrier-frequency amplification is indispensable at least for pictures involving more than the average 5 number of lines and average fineness. The rapid interruption of the scanning light employed in picture telegraphy for the production of such a carrier frequency by the aid of a perforated disk is mechanically impracticable because of the brief scanning time required for a picture element or unit. Periodic alteration of the intensity of the scanning light source itself has also not yet been realizable in practice. It has therefore been 10 attempted by electrical ways and means to produce the carrier frequency by superposing a radio frequency alternating current potential upon the direct current potential acting upon the photoelectric cell and then compensate for the wattless current flowing by virtue and by way of the electrode capacity by 15 neutralizing circuit schemes.

This complication which is inconvenient in practice can be obviated according to the 20 present invention by introducing in the circuit of the photoelectric cell a radio frequency variable "conduction" resistance having the function of a pure interrupter rather than a radio frequency alternating current potential. To be sure, an attempt has previously been made, with the same end in view, to connect a second photoelectric cell in the 25 circuit of the photoelectric cell subject to the action of the scanning light pencil, said second cell being struck by light subject to high-frequency interruptions with the result that its conducting power is periodically altered. However, the chief drawback of such scheme resides in the extremely high electric resistance 30 of the interrupter photoelectric cell whereby the picture currents generated in the scanning cell are considerably weakened.

This disadvantage has been obviated by 35 the arrangement hereinafter to be disclosed in more detail. The method consists in providing a Faraday cage in series with the scanning photoelectric cell in which, owing to the temporary entrance of the pendulous or intermittent cathode-ray pencil of a sort of 40 Braun tube, high-frequency conductivity

variations are occasioned. One form of construction and practical embodiment is shown in the drawing, where numeral 1 represents the scanning photoelectric cell which in the 45 analysis or exploration of the picture to be transmitted is struck by light in the direction of the arrow; numeral 2 denotes the "suction" or anode electrode of the cell 1; 3 is the light-responsive electron-emissive electrode of cell 1; 4 is the anode or suction-current battery; 5 is the coupling resistance associating with 50 amplifier tube 7; and 6 is a source of potential adapted to regulate the grid biasing potential. Inside a Braun tube 10 is a Faraday cage consisting of the screen electrode 8 having a hole, 55 and of the plate 9 which is located at close proximity to the screen. The plate 9 is then connected with the suction or anode electrode 2 of the photoelectric cell 1. The parts of the 60 cell 1 could also be constructionally united with the tube 10, for instance, in such a way that the emissive surface 3 exposed to the action of light is periodically struck directly by the electron pencil of the Braun tube. Numeral 12 represents the source for heating the 65 cathode 11.

The electrons issuing from the hot cathode and accelerated from the potential source 14 pass through the anode 13 which in well-known manner is shaped tubular. The 70 cathode-ray pencil emerging therefrom passes through the electrostatic deflective field set up between the plates 15, though in lieu thereof also magnetic deflector coils could be employed. The cathode-ray pencil is subjected to spatial oscillations or pendulous motions by means of a radio frequency generator which charges the pair of plates 15 by way of a transformer 16, 17. As a result the said 75 pencil is alternately caused to pass through the hole in the plate 8 and to be precluded from striking the interior of the Faraday cage by striking the side of the electrode 8. But every time that the cathode-ray pencil enters 80 between electrode 8 and member 9, it produces high conductivity inside the cage which could be greatly assisted and enhanced by residual gases as well as by secondary electron emission at the plate 9, with the result that the 85 resistance which previously was practically 90

50 55 60 65 70 75 80 85 90 95 100

infinitely high is greatly diminished. In this way the device acts like an inertialess interrupter adapted to chop at radio frequency rate the picture-currents generated in cell 1.

5 The plate 8 is grounded so that it will always be kept at ground potential.

Instead of resorting to spatial reciprocation of the electron pencil in the tube 10, periodic action upon the space between members 8 and 9 can be effected also when the axis of the cathode-ray pencil is stationary by causing a radio frequency alternating current potential to act between anode 13 and the heated cathode 11 in lieu of a direct current potential. In that case the deflector device 15 is superfluous.

Having now described my invention, what I claim and desire to secure by Letters Patent is the following:

20 1. In combination, a translating element to convert energy of predetermined wavelengths supplied thereto into electric energy, an amplifier having one input terminal connected with one terminal of the translating element, a plurality of electrode elements normally electrically insulated one from the other, a connection between one electrode element and a second terminal of the translating element, and a connection between a second electrode element and a second input terminal of the amplifier, means for generating a cathode ray, means to reciprocate the generated ray across the electrode elements so as to introduce into the amplified output of the translating element an alternating current frequency which is modulated by the energy supplied to the translating element, said alternating current varying in amplitude from minimum to maximum by the cathode ray 35 establishing a path of zero conductive value between the electrode elements increasing in value progressively to a maximum upon the change in deflection of the ray from maximum to minimum deflection of the ray and 40 from maximum to minimum amplitude in reverse order, said minimum deflection producing between the plurality of electrode elements a substantially direct conducting path both by virtue of the contact established between the electrode elements by the cathode ray and by the secondary emission effects produced by the cathode ray upon at least one of the electrode elements.

2. In combination, a photoelectric cell for 55 converting varying intensities of light and shadow into proportionate strength electric current impulses, a Faraday cage comprising a pair of electrodes located in close proximity, said cage having one element thereof connected with an electrode of said photoelectric cell, a cathode ray tube in cooperative arrangement with the Faraday cage, means associated with the cathode ray tube for deflecting the cathode ray generated therein 60 for varying the conducting path between the

electrodes thereof periodically between zero and a crest value by spatially reciprocating the cathode ray pencil of the said Braun tube across said Faraday cage for introducing into said photoelectric cell a chopper frequency superposed upon the direct currents produced by light striking the photoelectric cell.

3. In combination, a photoelectric cell having one electrode thereof connected with the control electrode of a photo cell amplifier, a Faraday cage comprising a pair of electrodes located in close proximity, said cage having one element thereof connected with the second electrode of said photoelectric cell and a Braun tube arranged to project the controlled cathode ray pencil thereof towards said Faraday cage, and means cooperating with said Braun tube for spatially reciprocating said cathode ray pencil across said Faraday cage for varying the conducting power thereof between zero and a crest value so as to introduce into said photoelectric cell a chopper frequency to be superposed upon the direct currents produced by the action of light reaching the cell.

4. In combination, a photoelectric tube, an amplifier having one input terminal connected with an electrode of said photoelectric tube for amplifying the output currents from said photoelectric tube, a plate-like electrode connected with one of the electrodes of said photoelectric tube, a second electrode provided with a central aperture and arranged in close proximity to said plate-like electrode, said apertured electrode being connected operatively with a second input terminal of said amplifier, a cathode ray device for normally projecting cathode rays toward the aperture of said apertured electrode, and means for alternately moving the said cathode ray into and out of said aperture so as to vary periodically between a zero and a crest value the conducting path between said two electrode elements for introducing into the amplified photoelectric tube output an alternating current frequency which is modulated directly by the photoelectric currents.
